UNITED STATES PATENT OFFICE

2,567,754

FASTENING MEANS FOR SHOE SKATES

Gustav A. Almorth, Glastonbury, Conn.

Application May 6, 1947, Serial No. 746,233

7 Claims. (Cl. 280—11.32)

1

This invention relates to fastening means for shoe skates and more particularly to a means for detachably securing a skate to a shoe.

An object of this invention is to provide a highly practical and efficient fastening means on a skate which will engage a co-operating member on a shoe so that the skate may be firmly secured to the shoe or detached therefrom, with the use of a simple tool, in such a manner that no straps or the like will be required for securing the skate.

A further object of this invention is to provide such a fastening device which is highly efficient in its operation, easy to use, and economical to produce.

Further objects and advantages of this invention will be more clearly understood from the following description and from the accompanying drawings in which:

Fig. 1 is an elevational side view of a skate fastened to a shoe with my improved fastening means.

Fig. 2 is a bottom view of the shoe showing the co-operating fastening means thereon.

Fig. 3 is a plan view of the skate with the fastening means thereon.

Fig. 4 is an enlarged plan view of the fastening device embodying my invention.

Fig. 5 is a sectional side view thereof showing the same as attached to a portion of the shoe.

Fig. 6 is an elevational side view of the fastening device and a portion of the skate.

Fig. 7 is a plan view of a modified form of a fastening device embodying my invention.

Fig. 8 is a side view thereof, partly in central vertical section.

Fig. 9 is an elevational side view thereof, with a portion of the skate being shown in section.

As shown in the drawings, the numeral 5 denotes a skate, preferably an ice skate, which is detachably secured to a shoe 6 by my improved fastening means.

The fastening means are preferably mounted on the heel supporting portion 7 and the sole supporting portion 8, which portions may be incorporated in a single plate extending along the top of the skate, or may consist of separate plates as shown.

Each of my improved fastening devices preferably comprise a stationary clamping member 9 which is secured to the supporting plate of the skate, by such means as rivets 10, and extends through an opening 11 in said plate as clearly illustrated in Fig. 5 of the drawings.

A movable clamping member 12 is slidably supported in a bracket 13 which is secured to the sup-

2

porting plate, by such means as rivets 14, and has a groove 15 in the top thereof which receives the movable clamping member 12 and slidably supports said member under the supporting plate.

5 A clamp-operating rocking lever 16 is pivotally mounted within a slot 17 in the supporting bracket 13 by means of a shaft 18, and a screw 19 is threaded to a tail portion 20 of the said rocker lever and engages the bottom 21 of the slot 17. 10 The said screw 19 is provided with a suitable head to receive a wrench or key for rotating the screw to operate the fastening device.

The shoe is provided, both at the sole and the heel, with suitable members, such as the disks 22 and 23, to receive the clamping members of the fastening device. Each of these disks is firmly secured to their respective portion of the shoe by means of rivets 24, such as shown in Fig. 5, where the said disk 22 is shown secured to the heel 25. 15 The said disks are preferably fitted within a corresponding recess in the shoe so that they are flush with the bottom surface of the shoe at the sole and heel, and the upper corner of the disk is beveled to correspond with the angle of the 20 clamping members 9 and 12.

The shoe is also provided with recesses 26 and 27 at opposite sides of the disk 22 which extend over the edge of the disk to provide an undercut for receiving the ends of the clamping members 9 and 12 as clearly illustrated in Fig. 5 of the drawings.

In the preferred form of my fastening device, the disks 22 and 23 are provided with opposite notches, as at 28 and 29, which register with the 30 recesses 26 and 27. These notches are preferably curved, and the clamping members 9 and 12 are also correspondingly curved so as to set within the said notches and prevent longitudinal movement of the skate relatively to the shoe.

In the form illustrated in Figs. 7 to 9, the disk 30 is provided with an unbroken circumferential surface and the clamping members, such as the member 12a shown in Fig. 8, are correspondingly curved so as to embrace a portion of the circumference and not only prevent movement of the disk crosswise to the clamping members, but also to secure the skate on the shoe against relative longitudinal movement.

In the operation of my improved fastening 50 means, as illustrated in Figs. 1 to 6, the skate is placed upon the shoe with the clamping members 9 and 12 fitting into the recesses 26 and 27 in the heel of the shoe and 26a and 27a in the sole of the shoe. The screw 19 is then rotated 55 so as to push against the bottom 21 of the slot

17 and rock the upper portion 20a of the lever 16 inwardly against the slidable clamp 12 and force said clamping member against the edge of the disk 22, thus clamping the said disk firmly between the clamping members 9 and 12 and firmly securing the skate to the shoe against lateral and longitudinal relative movement.

When it is desired to remove the skate from the shoe, the member 19 is simply turned in the opposite direction and the rocker lever will permit the clamping member 12 to become loosened and thereby readily released from the disk 22.

It will be clearly understood from the above description that by the provision of the notches 28 and 29, in the sides of the disk 22, and the convex clamping surface on the members 9 and 12, the fastening member is automatically located with its axis extending across the longitudinal axis of the disk 22, when mounted on the shoe, and will thereby prevent movement of the skate relative to the shoe. Also, in the form illustrated in Figs. 7 to 9, wherein the clamping member is provided with a concave inner surface, the clamping disk will be received on the axis of the clamping members so that longitudinal movement of the skate relative to the shoe is also prevented.

In the forms illustrated in said Figs. 7 to 9, the movable clamping member 12a is operated by means of a screw 31 which is threaded to the bracket 32 and has a flange 33 and a wrench receiving head 34. A washer 35 is preferably provided between the flange 33 and the clamping member 12 to relieve friction, and the said washer may be provided with a retaining prong 36 which extends over the edge of the flange 33 so as to retain the said washer upon the shank 37 of the screw. In this form, when the screw 31 is rotated for clamping operation of my fastening device, the flange 33, through the washer 35, will force the slidable clamping member 12a against the disk 30 and thereby clamp said disk firmly as above described.

It is pointed out that by forming the clamping members either with concave or convex shape, as illustrated, they may be constructed of sheet metal and reinforced by such formation so as to prevent bending thereof under the clamping pressure applied to them in the use of my improved fastening means. It will also be noted that all of the mechanism comprised in the said fastening means is so constructed as to provide the maximum strength as well as rapidity and ease of operation.

I claim:

1. In a fastening device for fastening a skate having a supporting plate to a shoe, wherein a keeper disk is set into the bottom of the sole and heel of the shoe and wherein the bottoms of the sole and heel are notched at diametrically opposite sides of the keeper disks to provide clearance for clamping members of the fastening device; said device including a stationary clamping member projecting upwardly through an opening in said plate, a movable clamping member also projecting upwardly through an opening in said plate, both of said clamping members being engageable with marginal edges of the keeper disk at said notched portions, a bracket secured to the underside of said plate and slidably supporting said movable clamping member, a rocker lever pivotally carried by said bracket, and a screw through said lever for forcing the movable clamping member into clamping position.

2. In a fastening device for fastening a skate having a supporting plate, to a shoe wherein a keeper disk is set into the bottom of the sole and heel of the shoe and wherein the bottoms of the sole and heel are notched at diametrically opposite sides of the keeper disks to provide clearance for clamping members of the fastening device; said device comprising a clamping member projecting upwardly from said supporting plate, a bracket secured to the underside of said plate, a movable clamping member slidably supported on said bracket and projecting upwardly through an opening in said plate, both of said clamping members being engageable with marginal edges of the keeper disk at said notched portions, said bracket having a slot therein, a lever pivotally mounted in said slot and having a portion engaging said movable clamping member and a portion depending therefrom, and a screw member threaded to said depending portion and engaging the bottom of said slot for rocking said lever to force said movable clamping member toward the first clamping member.

3. In a fastening device for fastening a skate having a supporting plate to a shoe, wherein a keeper disk is set into the bottom of the sole and heel of the shoe and wherein the bottoms of the sole and heel are notched at diametrically opposite sides of the keeper disks to provide clearance for the clamping members of the fastening device; said device comprising a stationary clamping member secured to the underside of said plate and projecting upwardly through an opening therein and inclined at an angle toward the longitudinal axis of the skate, a bracket secured to the underside of said plate, a movable clamping member positioned oppositely to said stationary clamping member and slidably mounted on said bracket against the underside of said supporting plate and projecting upwardly therefrom and also inclined at an angle toward the said axis of the skate, both of said clamping members being engageable with marginal edges of the keeper disk at said notched portions, and screw-operated means for forcing the said movable clamping member in the direction of the first clamping member for clamping engagement with the keeper disk.

4. A fastening device for attaching a skate having a supporting plate to a shoe, a stationary clamping member projecting through an opening in said plate, a movable clamping member positioned opposite said stationary member, a bracket secured under said plate and having a groove therein slidably positioning said movable clamping member, screw means carried by said bracket for operating said movable clamping member, a keeper disk disposed within a recess in the bottom of the shoe, the said keeper disk having a tapered surface on the peripheral edge thereof adapted to contact the said clamping members, there being a recess at each of the opposite sides of said keeper disk to permit said disk to fit between the clamping members against the surface of the skate with the said clamping members projecting above the keeper disk.

5. A fastening device for detachably securing a skate to a shoe comprising a pair of clamping members relatively movable on said skate and having convex engaging surfaces, screw means for forcing said clamping members into relative clamping position and a keeper disk secured to the bottom of the shoe; said keeper disk being adapted to fit between the said clamping mem-

bers and having curved notches in the edge thereof for the reception of said convex engaging surfaces on the said clamping members to thereby prevent relative lateral movement between the disk and clamping members.

6. A fastening device for detachably securing a skate to a shoe comprising a pair of clamping members relatively movable on said skate and having concave engaging surfaces, screw means for forcing said clamping members into relative clamping position and a keeper disk secured to the bottom of the shoe, said keeper disk being adapted to fit between the said clamping members and having curved peripheral engaging portions adapted to receive the said concave surfaces of the clamping members to thereby prevent relative lateral movement between said disk and clamping members.

7. In a fastening device for fastening a skate having a supporting plate to a shoe, wherein a keeper disk is set into the bottom of the sole and heel of the shoe and wherein the bottoms of the sole and heel are notched at diametrically opposite sides of the keeper disks to provide clearance for clamping members of the fastening device; said device comprising a stationary clamping member secured to said supporting plate and extending upwardly through an opening therein,

a bracket secured to the underside of said plate, a movable clamping member slidably mounted on said bracket and extending upwardly through an opening in the plate, both of said clamping members being engageable with marginal edges of a keeper disk at said notched portions, a screw threaded to said bracket, an annular flange on said screw extending into the opening in said supporting plate and abutting the said movable clamping member and means for rotating said screw to force said flange against said movable member and thereby move said member into clamping position.
